Specification for Design.

Patented Oct. 18, 1921.

Application filed December 31, 1920. Serial No. 434,377. Term of patent 7 years.

(GRANTED UNDER THE PROVISIONS OF THE ACT OF MARCH 3, 1921, 41 STAT. L., 1313.)

To all whom it may concern:

Be it known that we, ALBERT ROMEZ-CUILLIEZ, commonly called ALBERTILUS, and JEAN CÉLIER, citizens of the French Republic, residing at 28 Rue Jean-Burguet, Bordeaux, in the Republic of France, have invented a new, original, and ornamental Design for a Game-Board, for which I have filed an application in France, July 15, 1920, No. 21, of which the following is a specification, reference being had to the accompanying drawing, forming part thereof.

The figure is a plan view of a game board, showing our new design.

We claim:—

The ornamental design for a game board, as shown.

ALBERT ROMEZ-CUILLIEZ, dit ALBERTILUS.
JEAN CÉLIER.
